Primary Examiner — Jennifer L Watkins*(74) Attorney, Agent, or Firm* — Cermak Nakajima McGowan LLP; Adam J. Cermak(57) **CLAIM**

The ornamental design for footwear heel, as shown and described.

DESCRIPTION

Fig. 1.1 is a top, left, front perspective view of a footwear heel, showing my new design the opposite side being a mirror image thereof;

FIG. 1.2 is a front elevational view of the footwear heel shown in FIG. 1.1;

Fig. 1.3 is a bottom, left, front perspective view of the footwear heel shown in fig. 1.1 the opposite side being a mirror image thereof; and

FIG. 1.4 is a top plan view of the footwear heel shown in FIG. 1.1.
